UNITED STATES PATENT OFFICE.

FRANK E. BOCORSELSKI, OF RICHMOND, VIRGINIA.

TAP AND REAMER.

Specification of Letters Patent.

Patented Oct. 8, 1912.

1,040,610.

Application filed August 5, 1912. Serial No. 713,207.

To all whom it may concern:

Be it known that I, FRANK E. Bocor-
SELSKI, of Richmond, in the county of Hen-
rico and State of Virginia, have invented a
certain new and useful Improvement in
Taps and Reamers, of which improvement
the following is a specification.

My invention relates to taps and reamers
for truing and cutting screw threads in
holes in pieces of metal, and its object is to
provide means whereby the guides and driv-
ing stems of taps and reamers may be
readily and quickly detached from and at-
tached to the bodies of said cutting tools,
and be held securely connected thereto dur-
ing their operation, thereby enabling it to
be carried on in locations where limitation
of space would interfere with that of a tap
or reamer of the ordinary construction.

The improvement claimed is hereinafter
fully set forth.

In the accompanying drawings: Figure 1
is a view, partly in elevation and partly in
longitudinal central section, of a stay bolt
tap and reamer, illustrating an embodiment
of my invention; Fig. 2, a similar view
showing a structural modification; Fig. 3,
a longitudinal central section, on an en-
larged scale, through a portion of the ap-
pliance shown in Fig. 1; Figs. 4 and 5,
transverse sections on the lines *a a* and *b b*,
respectively, of Fig. 3; Fig. 6, a view, partly
in elevation and partly in longitudinal cen-
tral section, of a tap showing a further
structural modification; and, Figs. 7 and 8,
transverse sections, on the lines *c c* and *d d*,
respectively, of Fig. 6.

It is necessary for the operation of taps,
reamers, and metal cutting tools of similar
character, in certain classes of work, that
their bodies should be provided with a
guide stem at one end of their cutting mem-
bers, and a driving stem at the other, and
these stems, which are often of considerable
length, have ordinarily been integral with
the bodies of the tools. When operating
in situations where space is limited, as in
the combustion chambers of steam boilers,
inconvenience and delay is often occasioned
by reason of the projecting stems coming in
contact with parts of a structure other than
those on which the work is being done, so
that time is lost in the backing out of the
tool which often becomes necessary. My in-
vention avoids this objection by providing
stems which are quickly detachable and at-

tachable as conditions may require, while
being so connected to the bodies of the tools
as to be exempt from liability to accidental
and undesired detachment during their op- 60
eration.

Referring first to Figs. 1 and 3 to 5 in-
clusive, my invention is herein exemplified
as applied in connection with a stay bolt
tap and reamer, the body, 1, of which is
provided with the usual screw cutting
threads, 1^a, and reaming cutters, 1^b. In
the practice of my invention, a driving
stem, 2, is detachably connected to one end
of the body of the tool, and a guide stem, 3,
is similarly connected to the opposite end
thereof, the connection being effected, in the
application to taps and reamers of the or-
dinary construction, by the following
means. An externally threaded extension,
1^c, is formed on each end of the body, 1, and
a cylindrical stem, 4, is screwed on each of
said extensions. The coupling stems are
reduced in diameter beyond the portions
which engage the extensions, 1^c, and their 80
so reduced portions are fitted truly in cor-
responding bores in the adjacent ends of
the driving stem, 2, and guide stem, 3, the
ends of which abut against shoulders at
the ends of the larger diameter portions of 85
the coupling stems, 4, as clearly shown in
Fig. 3. Rotation of the driving and guide
stems, 2 and 3, relatively to the coupling
stems, 4, and the connected body of the tool,
is prevented by transverse pins, 5, fixed in 90
the coupling stems and engaging longitudi-
nal slots, 6, in the driving and guide stems,
which slots are open at the ends of said
stems. Accidental longitudinal displace- 95
ment of said stems from their normal posi-
tions on the coupling stems, 4, is prevented
by yielding spring catch mechanisms, each
of which comprises a pair of ball latches,
7, fitting in a transverse opening, 4^a, in one 100
of the coupling stems, and forced into en-
gagement with an internal groove or socket,
7^a, in the connected guide stem or driving
stem, by an interposed spring, 7^b. The ball
latches are held in position by a nut, 7^c,
which partially incloses one of them and 105
is screwed into the end of the opening, 4^a.
If preferred, a single ball latch, operating
similarly to each of the two similar mem-
bers described, may be used in each mech-
anism.

It will be obvious to those familiar with
the manipulation of taps, reamers, and an-

alogous metal cutting tools, that a construction substantially as above described, is readily applicable, at inconsiderable cost, to such tools, and that, in their operation, the 5 driving and guide stems will be securely held to the tool, and the detachment and attachment of either or both of them may be instantly effected when necessary or desirable.

10 Fig. 2 illustrates a structural modification which is desirably applicable in the manufacture of new tools, and differs from the construction first described only in the particular that the coupling stems, 4, are, 15 in this case, made integral with the body, 1, of the tool, instead of being screwed to threaded extensions thereof. The means for preventing independent rotation, and accidental longitudinal displacement of the 20 driving and guide stems are similar to those before described.

Figs. 6 to 8 inclusive show a stay bolt tap, having an integral driving stem, 2, formed on one end of its body, 1, and having its 25 body bored out at, and for a substantial distance from, its opposite end, to receive a guide stem, 3, which is reduced in diameter at its end adjoining the body for a distance corresponding substantially with the length 30 of the bore of the body and is fitted truly therein. Rotary movement of the guide stem, relatively to the body of the tool, is prevented by a pin, 5, fixed in the guide stem and engaging open ended slots, 6, in 35 the adjoining end of the tap body, and a yielding spring catch mechanism similar to that before described is provided for preventing accidental longitudinal displacement of the guide stem, 3, the ball latches, 40 7, in this case fitting in the guide stem, and engaging recesses in the body of the tap.

It will be seen that this construction embodies the same structural and operative principles as those before described, the 45 structural difference being the immaterial one that in this case, the engagement of the stem with the body is effected by fitting the stem within the body, while in the former cases, the extensions of the body are fitted 50 within the stems.

I claim as my invention and desire to secure by Letters Patent:

1. The combination, with a metal cutting

tool having peripheral cutting members on its body, of a stem longitudinally engaging one end of the body of the tool, and connected detachably thereto by a slip joint. 55

2. The combination of a metal cutting tool having peripheral cutting members on its body, a stem longitudinally engaging one 60 end of the body, means for preventing independent rotary movement of the stem, relatively to the body, and means for preventing accidental longitudinal movement of the stem, relatively to the body. 65

3. The combination of a metal cutting tool having peripheral cutting members on its body, a stem longitudinally engaging one end of the body, a transverse pin fixed in one of said engaged members and fitting 70 open ended longitudinal slots in the other, and means for preventing accidental relative longitudinal movement of said engaged members. 75

4. The combination of a metal cutting tool having peripheral cutting members on its body, a stem longitudinally engaging one end of the body, means for preventing independent rotary movement of said engaged members, and a yielding spring catch mechanism 80 interposed between the body and stem for preventing accidental relative longitudinal movement of said engaged members. 85

5. The combination of a metal cutting tool having peripheral cutting members on its body, a stem longitudinally engaging one end of the body, a transverse pin fixed in one of said engaged members and fitting 90 open ended longitudinal slots in the other, and a yielding spring catch mechanism interposed between said engaged members for preventing accidental relative longitudinal movement thereof. 95

6. The combination of a metal cutting tool having peripheral cutting members on its body, a stem longitudinally engaging one end of the body, means for preventing independent rotary movement of said engaged members, a ball latch fitted in one of said engaged members and engaging a socket in 100 the other, and a spring normally holding said ball latch in engagement. 105
